UNITED STATES PATENT OFFICE.

ANDERS HAGQVIST, OF SOUTH BEND, INDIANA.

PLOW.

SPECIFICATION forming part of Letters Patent No. 396,204, dated January 15, 1889.

Application filed July 26, 1888. Serial No. 281,153. (No model.)

To all whom it may concern:

Be it known that I, ANDERS HAGQVIST, of South Bend, in the county of St. Joseph and State of Indiana, have invented certain new and useful Improvements in Plows; and I do hereby declare that the following is a full, clear, and exact description thereof, reference being had to the accompanying drawings, and to the letters of reference marked thereon, which form part of this specification, in which—

Figure 1 is a side view of my improved plow, the share being turned to the side of the landside opposite to that shown. Fig. 2 is a vertical sectional view through Fig. 1 in the plane of the beam, shoe, and landside. Fig. 3 is a sectional view similar to Fig. 2, but showing the position of the parts when the lever is retracted and the mold-board is partly turned over the shoe. Fig. 4 is a plan view showing the share and handles in different positions by the aid of dotted lines. Fig. 5 is a rear view, the handles being removed. The remaining figures are detail views of various portions of the plow.

This invention is an improvement in what are generally known as "hillside-plows;" and its objects are to provide a simple and efficient mechanism for shifting the mold-board to the right or left of the landside or beam without the necessity of lifting the plow-shoe, so that the furrow can be cut either right or left hand, as the plowman wishes; to provide means for backing and elevating the plow-beam without moving the landside or handles, so that the beam will be out of the way of the mold-board when the latter is shifting; to make the shifting of the beam and mold-board simultaneous; to adjustably attach the handles to the shoe of the plow or landside, so that they can be shifted to suit the position of the mold-board and locked in such position; to provide improved attachments of the shifting mold-board to the landside or shoe, whereby the mold-board will be properly braced to sustain the thrust and pressure of the earth thereagainst, and, finally, to so connect the operating mechanisms of the mold-board, beam, and locking device for the handles that they can all be actuated by the movement of a single lever conveniently placed for operation by the

plowman. These objects are attained in my present invention, which may be readily understood from the following description.

Reference being had to the accompanying drawings by letter, A designates the shoe of the plow, upon the bottom of which is secured or formed the landside a, which is preferably made sufficiently wide at bottom to support the weight of the shoe and beam without sinking into the ground when the mold-board is being turned, and this landside is dressed on both sides, so that the furrow can be cut either right or left of the same. The shoe A is angular, being pointed at front and widened vertically at rear, and in its upper front face is formed an inclined socket, B, and this socket communicates with a similarly-inclined channel, b, which in reality forms but a continuation of the socket at the top and rear of the shoe. The side walls of channels b are extended rearward beyond the shoe, forming opposite downwardly-inclined arms or lugs C C, for a purpose hereinafter referred to.

D is the plow-beam, which is of ordinary hook form, its short lower arm or foot, d, being dressed to fit nicely in socket B and channel b, which are angular in cross-section, preferably, to prevent rocking of the beam on the shoe. When the foot d is seated in the socket, the beam is in proper working position, and forward draft thereon only binds it more securely in the socket and draws the shoe with it. The beam is vertically slotted at its bend, as shown at E, said slot extending into foot d, and in said slot, near the lower end thereof, is pivotally secured on a bolt, e, the front end of a link, F, the other end of which is pivotally connected to the end of an arm, f, mounted on a short shaft, G, journaled between the arms C C of the shoe, as shown, and which arm f can be rocked by an up-standing lever, g, so that the plow-beam is longitudinally movable and can be drawn backward on the shoe, partly disengaging it from socket B, as is evident. In order to prevent the beam being drawn too far rearward, and also to prevent too much strain being put on the mouth of socket B and end of foot d when the beam is retracted should the team attached to the beam start, I may employ a transverse key piece or boss, H, secured to or

formed on the lower edge of beam D in front of pin e, the ends of which key work in inclined slots h h, formed in the side walls of channel b, as shown.

- 5 The mold-board I is double-faced, and is formed with two similar but oppositely-curved wings, i i, and its share or point J is made triangular, as shown, its side edges, j j, being sharpened and so bent that if the share be
  - o turned to either right or left side of the shoe one of the edges j will be in a horizontal and the other in a vertical position, thus forming cutting and shear edges of the share, while the lowermost wing or face i will properly
- 5 turn the earth as the plow progresses. The mold-board can thus be shifted to right or left of the shoe and still be in working condition. Other well-known forms of double shares or mold-boards might be employed;
  - o but I prefer that described. The share has a shoulder, K, on its under surface near its front end and in line with the apex of point J, and this shoulder fits over the front end of the shoe A and landside and is pivoted to the
- 5 front end of the shoe by a horizontal bolt, k. The rear portion of the mold-board is supported by a shifting quadrant, L, which consists of a bell-crank brace, l, pivoted at its angle by a bolt, m, in a transverse slot, M, through
  - o the shoe, so that the arms of the brace are on opposite sides of the shoe. To the ends of the brace-arms are secured the ends of an arc-shaped rod, N, which passes through a series of eyes, n n, attached to a cross-brace, O, on the under side of the mold-board. The rod N is longer than the width of mold-board I, so that the latter has a certain amount of lateral play thereon; but any pressure exerted on the face of the mold-board is instantly
    - o transmitted to the pivot of the quadrant L on the shoe A.

Brace O has a central eye, o, to which is pivotally attached the end of a link, P, the other end of which is similarly attached to

- 5 an eye, p, secured to the plow-beam near the upper end of slot E. When the mold-board is down, the link P stands at right angles, or nearly so, with the share and beam; but when the beam is retracted the link is drawn backward. The mold-board being pivotally mounted on the shoe, as described, the retraction of the beam through link P turns the mold-board on its pivots and brings it up centrally over the shoe.

5 It will be observed that the wings of the mold-board extend rearward beyond the bend of the beam, so that in order to shift the mold-board over the shoe it is necessary to get the beam out of the way. This is effected by the

- o lever g and connections, as described. The operator, by giving a rearward pull on the lever, causes the beam to slide backward and upward on shoe A, and the link P simultaneously draws the mold-board up over the shoe, but beneath the longer arm of the beam. When in this position, the mold-board will

by momentum pass the center of gravity and incline toward the opposite side of the shoe, and the operator by then giving the lever a forward thrust pushes back the beam to its

- 70 proper position on the shoe, and simultaneously through link B forces the mold-board downward on the side of the shoe opposite its position before the beam was retracted.

The mold-board in moving to its new position oscillates the quadrant and causes it to drop toward the mold-board, so that it follows and braces the mold-board in either of its positions. The vertical edge of point J will always be in proper line with the side of

- 80 the landside, and the arm of brace l will be upright and out of the way on the landside.

Q q are the similar opposite handles, converging at their lower ends and united by a loop, R, which is journaled on a spindle or

- 85 bolt, r, in the heel of the shoe, as shown, so that the handles may be shifted laterally. The handles are connected near their lower ends by a segmental plate, S, which has notches
  - 90 s s near its opposite ends.

T is a plate having ears t t, embracing the arms C C and suspended from shaft G, and also having a front curved portion, U, that embraces segment S and holds the handles in proper upright position. The curved portion

- 95 U is vertically perforated at u for the passage of the tooth v of a dog, V, mounted on shaft G and connected with lever g, so as to be operated thereby. Handle Q is on the right and handle q on the left, and when the plow-beam
  - 100 has been retracted and the mold-board thrown toward the right side of the shoe, as described, the handles can be shifted on their pivot to bring handle q in line with the left-hand side of the landside or shoe. This brings the left
    - 105 notch s of segment S beneath the curved portion U of plate T, and when lever g is thrown forward, as described, dog V is thrown upward, its tooth v passing through the opening in part U, and also through the left recess
      - 110 s of segment S, whereby the handles are locked to plate T and lateral motion thereof is prevented.

When the mold-board is shifted to left of the shoe, the handles (which are released by

- 115 the movement of lever g necessary to shift the beam backward) can be shifted to bring handle Q in alignment with the right-hand side of the landside. The arm f and dog V being rigidly connected with lever g, the parts
  - 120 are operated synchronously, as is evident.

The draft on beam D, after it is retracted, will materially assist the plowman in working the parts, and the lever g could be made so long that but little power is required to operate it. The lever g stands directly in front of and between the handles and moves in a vertical plane.

Having described my invention, I claim—

1. In a plow, the combination of a mold-board adapted to be shifted to right or left of the landside with a plow-beam adapted to

be retracted to permit turning of the mold-board over the landside, substantially as specified.

2. The combination, in a plow, of a shifting mold-board turning over the landside with a retractable plow-beam, and connections between the beam and mold-board whereby the mold-board is turned by the shifting of the beam, substantially as described.
- 10 3. The combination, in a plow, of a shoe, a retractable plow-beam thereon, and the mechanism for shifting said beam with a mold-board pivotally connected to the shoe and connected to the beam and adapted to be shifted to right or left of the beam over the shoe, substantially as described.

4. The combination of the landside and mold-board adapted to be shifted over and to right and left of said landside with the shifting-quadrant pivoted to said landside and bracing the mold-board and the laterally-adjustable handles, substantially as described.

5. The combination, with the shoe having a socket and the plow-beam having a foot sliding in said socket, of a mold-board adapted to be shifted over the shoe beneath the handle and the devices for retracting and shifting the beam while the mold-board is being turned, substantially as set forth.

30 6. In a plow, a shoe having a landside, a mold-board pivotally connected to and turning over said shoe, a pivoted shifting bracing quadrant for the mold-board, and a longitudinally-shifting plow-beam, all combined and arranged substantially as described.

7. The combination of the shoe, the mold-board pivotally attached thereto, the retractable plow-beam mounted thereon, and the adjustable handles with the lever-and-link connections, whereby the beam and mold-board are shifted and the handles locked simultaneously, substantially as described.

8. The combination of the shoe having an inclined socket, the shifting plow-beam having a foot engaging said socket, and the double-faced mold-board pivoted on said shoe and turning to right or left over the same with the short shaft journaled in the rear portion of the shoe, its arm and link-connection between the same and plow-beam, and the link-connection between said beam and mold-board, whereby the beam is shifted and the mold-board turned upon the oscillation of said shaft, substantially as described.

55 9. The combination of the slotted and channeled shoe and the shifting plow-beam having a foot engaging in the socket of the shoe with a transverse key attached to said beam and engaging in slots in the walls of the channel to prevent the escape of the beam from the shoe, substantially as specified.

10. In a plow, an angular-pointed shoe hav-

ing an inclined slot and a channel slotted at the sides and ending in arms at the rear upper portion of the shoe, a mold-board adjustable to right or left of the shoe and pivotally attached thereto, a quadrant-brace pivoted to the shoe and supporting the wings of the mold-board, an adjustable beam having a foot mounted in the socket and channel of the shoe and keyed in the slots of said channel, a lever pivoted to a shaft journaled in the arms of said shoe, the link-connections between said shaft and beam, the link-connection between said beam and mold-board, and the adjustable handles, all combined and constructed substantially as set forth.

11. The combination of the shoe A and the mold-board I, having point J, pivoted to the front end of the shoe and provided with a brace-piece, O, with the angular brace l, pivoted in a slot in the rear of the shoe, the arc-shaped rod N, secured to the arms of said brace, and the eyes n, attached to brace O and engaging bar N, all substantially as specified.

12. The combination of the shoe with the mold-board I, having wings i and point J, and brace O, provided with eyes o o, with the brace l, pivoted in a slot in said shoe and having its arms on opposite sides of the same, and the rod N, passing through eyes o o and attached to the ends of brace l, and the handles attached to said shoe in rear of the brace, substantially as and for the purpose set forth.

13. The combination of the shoe A, having landside a and inclined socket B, channel b, and arms C C, and the shifting mold-board pivotally mounted on said shoe, with the slotted beam D, having foot d, engaging socket B, the shaft G, journaled in arms C C, the lever g, the arm f and link F, connecting the shaft and beam, and the key H and slots h, all substantially as and for the purpose set forth.

14. The combination, in a hillside-plow, of a foot, A, having inclined socket B and channel b, arms C C, the beam D, having foot d, engaging socket B, and the shaft G, lever g, arm f, and link F, for shifting the beam, with the mold-board I, having share J, formed with shoulder K on its under side and pivoted on the front end of the shoe, the quadrant L, pivoted to the shoe and supporting the wings of said mold-board, the link P, connecting said mold-board and beam, and the adjustable handles and their locking devices operated by lever g, all constructed and arranged substantially as set forth.

In testimony that I claim the foregoing as my own I affix my signature in presence of two witnesses.

ANDERS HAGQVIST.
